UNITED STATES PATENT OFFICE

159,767

COMBINED HANDBAG AND UMBRELLA
HOLDER

George Weinstein, New York, N. Y.

Application February 2, 1950, Serial No. 7,667

Term of patent 3½ years

(Cl. D87—3)

To all whom it may concern:

Be it known that I, George Weinstein, a citizen of the United States of America, residing in New York, county of New York, and State of New York, have invented a new, original, and ornamental Design for a Combined Handbag and Umbrella Holder, of which the following is a specification, reference being had to the accompanying drawing, forming part thereof.

Fig. 1 is a front perspective view of a combined handbag and umbrella holder showing my new design.

Fig. 2 is a rear perspective view thereof, a portion of the handle being broken away for convenience of illustration; and

Fig. 3 is a front perspective view of the article illustrating the handbag section and the umbrella holder section both in open positions and with the ends of the handle broken away for convenience of illustration.

I claim:

The ornamental design for a combined handbag and umbrella holder, substantially as shown and described.

GEORGE WEINSTEIN.
